[57] CLAIM

The ornamental design for a flatware holder or the like,
as shown and described.

DESCRIPTION

FIG. 1 is a top perspective view of a holder for flatware
or the like showing my new design.

FIG. 2 is an end elevational view thereof on an enlarged
scale.

FIG. 3 is a top plan view thereof.

FIG. 4 is a side elevational view thereof on an enlarged
scale.

FIG. 5 is a top plan view of my design of FIG. 1 showing
a modified form; and,

FIG. 6 is a top plan view of my design of FIG. 1 showing
another modified form.

The side and ends opposite those shown are substantially similar thereto, and the bottom portion of my holder for flatware or the like (not shown) is flat and unornamented.

FIG. 1.FIG. 2.FIG. 5.FIG. 3.FIG. 6.FIG. 4.
